Primary Examiner — Lauren R Calve(74) *Attorney, Agent, or Firm* — Banner & Witcoff, Ltd.(57) **CLAIM**

The ornamental design for a package with lid, as shown and described.

DESCRIPTION

FIG. 1 is a top, front, right perspective view of the claimed design for a package with lid;

FIG. 2 is a front view thereof;

FIG. 3 is a back view thereof;

FIG. 4 is a left view thereof;

FIG. 5 is a right view thereof;

FIG. 6 is a top view thereof;

FIG. 7 is a bottom view thereof; and,

FIG. 8 is a top, front, right perspective view of the claimed design in an alternative configuration.

The broken lines immediately adjacent to the shaded area depict boundaries of the claimed design and form no part thereof. The broken lines showing the remainder of the package with lid depict environmental structure and form no part of the claimed design.
